UNITED STATES PATENT OFFICE.

C. B. GARLINGHOUSE AND G. B. GARLINGHOUSE, OF ALLENSTVILLE, IND.

IMPROVEMENT IN HARVESTERS.

Specification forming part of Letters Patent No. 24,803, dated July 19, 1859.

To all whom it may concern:

Be it known that we, C. B. GARLINGHOUSE and G. B. GARLINGHOUSE, of Allensville, in the county of Switzerland and State of Indiana, have invented a new and useful Improvement in Harvesters; and we do hereby declare that the following is a full, clear, and exact description thereof, reference being had to the accompanying drawings, and to the letters of reference marked thereon and made to form a part of this specification.

Our invention relates to certain improvements in harvesters for the better protecting and operating the mechanism of the machine, hereinafter to be described.

In reference to the accompanying drawings, Figure 1 represents in perspective an external view of our invention with its parts arranged for operation. Fig. 2 is a transverse sectional view showing the device for throwing the machinery in and out of gear. Fig. 3 is a longitudinal sectional view of the cam-wheel, showing the arrangement of the cams and the reciprocating central bar. Fig. 4 is a transverse sectional view showing the manner of operating the sickle.

A is the frame-work of the harvester.

B is a cam-wheel, the inner side of the periphery of which is formed with a series of cams, B', as shown in Fig. 3.

C is a disk made to fit within the periphery d upon the inner side of the disk C. Passing through a slot in the axle-tree g is a reciprocating bar, b, which is secured in its vertical position by means of the arms e, which are pivoted to the disk C at i, so that an easy vertical reciprocating motion may be imparted to the bar b. The bar b is secured from falling inwardly by means of clasps h, as shown in Fig. 3, so that although it is permitted to reciprocate without material friction it is still secured to the disk in such manner that it may be thrown in and out of gear with the cam B'

by a lateral motion of the said disk C. The bar b is provided at its ends with friction-rollers f, which are adjusted with reference to the cams B' in such manner that the bar b may be made to reciprocate vertically as the wheel B rotates, as shown in Fig. 3.

j is a bent lever, pivoted to the post k at k', and extending therefrom through slot l of the disk C to the bar b, in which the end j' is loosely inserted. The opposite end, j'', is extended downward to a convenient point for attaching the sickle, as represented.

m is a bent rod, attached to the disk C, by means of which the disk C is withdrawn from the wheel B and the bar b thrown out of gear with the cams B', so that the wheel may rotate without giving motion to the sickle.

The operation of our invention may be briefly described as follows: The bar b being in gear with the cams B' and the wheel being made to rotate, the bar b will be made to reciprocate vertically, thereby operating the bent lever j, and imparting a corresponding reciprocation horizontally to the sickle attached to the end j'' of the lever j, thereby operating the sickle in the most efficient manner.

We do not claim operating harvester-cutters by cam-wheels, rock-shafts, or bent levers; nor do we claim, in the broad, closing the movements in a box; but

What we claim as our invention, and desire to secure by Letters Patent, is—

The peculiar arrangement of the disk C in relation to the mechanism for operating the cutters, the standard k, and sliding frame m, in the manner and for the purpose specified.

In testimony of which invention we have hereunto set our hands.

C. B. GARLINGHOUSE.
G. B. GARLINGHOUSE.
